UNITED STATES PATENT OFFICE.

SILAS H. POMEROY, OF NEW ROCHELLE, NEW YORK.

FIREPROOF WINDOW.

1,025,995.

Specification of Letters Patent. Patented May 14, 1912.

Application filed February 24, 1909. Serial No. 479,709.

To all whom it may concern:

Be it known that I, SILAS H. POMEROY, a citizen of the United States, residing in the city of New Rochelle, county of Westchester, and State of New York, have invented certain new and useful Improvements in Fireproof Windows, of which the following is a specification.

This invention relates to improvements in fireproof windows, and refers more particularly to an improved adjustable parting strip and co-operative parts in a sheet metal window frame.

The salient objects of the invention are to provide a parting strip of that type which interfits with a sash arranged at either side thereof and which is made adjustable in the direction of the plane of the window, thereby securing as nearly perfect freedom of movement as is consistent with close fitting joints; to provide in such a construction means for adjusting the stop at various points throughout its length; to provide adjusting means for the purpose set forth which result in locking the stop positively in whatever position of adjustment it is placed; to provide a construction which may be very economically made and assembled; and in general to provide an improved construction of the character referred to.

In the drawings—Figure 1 is a fragmentary perspective view of a portion of the side frame of the window and fragments of sash adjusted therein, said window being equipped with my improvement; Fig. 2 is a cross sectional view taken on line 2—2 of Fig. 1 and looking downwardly; Fig. 3 is a cross sectional detail taken through the improved stop and associated parts in a plane co-incident with one of the adjusting screws; Fig. 4 is a view taken on line 4—4 of Fig. 2 and looking upwardly; Fig. 5 is an outside face view of a fragment of the adjustable side stop.

Referring to the drawings, 1 designates as a whole a hollow sheet metal window frame, within which are arranged to slide in the usual manner upper and lower sash members 3 and 4, respectively. The end rails in the window frame are not concerned in the present invention, and are not shown. Each hollow side frame member 2 is so constructed in cross section as to provide the usual fixed and integral jamb member 5 pro-

jecting inwardly along the exterior side of the frame, while in a corresponding position along its inner edge is arranged an adjustable stop 6, more particularly described hereinafter. The trough-like space between the two stops 5 and 6 is subdivided, as usual, by a parting strip 9, which latter, and its means of adjustment, constitute the present invention. The two channels thus formed, and designated 7 and 7', respectively, receive the upper and lower sashes 65 of the window, as shown. The parting strip 9 is preferably of T-shape in cross section, having its central or main body arranged to fit closely within a counter-channel 8 formed between the sash channels 7 and 7'. The head portion of said stop is provided with lateral flanges 10, 10', which flanges, as shown clearly in Fig. 2, extend within and engage corresponding grooves, as 24, formed in the side stiles of the respective sash.

In order that the parting strip 9 may be made bodily adjustable in the direction of the depth of the counter-groove 8, and adjusted at various points throughout the length of the strip, adjusting means are provided, which are preferably constructed as follows: Within the outer or head portion of the parting strip is arranged a strap-like metal reinforcement 11, which may be riveted in place, as indicated at 11'. Through this reinforcing strip 11 and the overlying wall of the stop are formed at intervals apart suitable screw apertures adapted to receive screws 12, and in order that said screws may have swiveling connection with the head portion of the stop, a cotter-pin or key 21 is inserted through the shank of each screw just inside of the reinforcement 11, after the screw has been properly inserted, as shown clearly in Fig. 3. These several grooves 12 at their threaded inner ends engage with what I term stations which are essentially studs or blocks 18. These blocks fit into socket members 17 of U-shaped cross-section, whose ends are deflected inwardly to engage in the grooves 14 provided in the sides of the blocks. To anchor the socket members in the counter grooves tongues 15 have their outer ends deflected to engage in the grooves 14 and have their inner ends extending through slots 15' at the inner corners of the grooves and are deflected over against the outer

sides of the grooves. The socket members are therefore securely anchored in the counter grooves, but the studs or blocks 18 may be adjusted longitudinally in the socket 5 members.

Each stud 18 is bored and internally threaded to receive the end of the screw, as indicated at 13, and in order to facilitate the entering of the point of the screw within the threaded socket, the mouth of the latter is countersunk, or made flaring, as indicated clearly at 19.

While the flanges 10 of the parting strip are shown in the present instance as projecting at right angles from the side walls of the strip, and the grooves in the sash stiles shaped correspondingly to receive said flanges, it is nevertheless to be understood that these interfitting or interlocking parts 20 may be variously shaped without departing from the invention. So also the specific construction of the adjusting device, whereby the parting strip is made adjustable within the counter-groove, may be varied 25 without departing from the invention in its broader aspects.

Preferably, in constructing window frames provided with parting strips embodying the invention herein described, one 30 of the stops is made adjustable toward and from the side stile of the sash, and is also made detachable. The stop 26, which is at the inner side of the window frame, is in the present instance made detachable, being 35 made hollow, applied to the face of the frame proper and secured thereto by screws 29. The heads of the screws 29 are received within counter-sunk eyelets 28. These eyelets 28 have an elongated slot 30 extending 40 transversely of the adjustable stop 6 as shown in dotted lines in Fig. 5. By loosening the screws slightly, the stop may be moved inwardly or outwardly toward or 45 from the sash stile, and thereafter secured in adjusted position by tightening the screws.

The utility of the adjustable parting strip is obvious to those skilled in the art. It may be noted, however, that by reason of the 50 adjustments provided, the flanges of the parting strip may not only be adjusted to exactly register with the grooves made to receive them in the stiles of the sash, but said flanges may be lined up so as to be straight and true regardless of any imperfection of manufacture or distortion of the 55 frame, due to setting it in the masonry or otherwise, thus insuring ease of movement and accuracy of fit between the sash and frame. Moreover, the parting strip may be 60 adjusted so as to bring a slight tension between the flanges and the grooves engaged thereby, thus improving the weathering qualities of the windows and absolutely preventing rattling. The adjustments once 65 made, it is obvious that the parting strip

will be held positively and without any tendency to lose its adjustment under operation of the window.

As hereinbefore indicated, modifications in the details of construction may be made 70 without departing from the invention, and accordingly I do not wish to be limited to the specific details herein described, except in so far as they are made the subject of specific claims.

I claim as my invention:

1. In a fireproof window, a side casing member provided with a longitudinal jamb channel, a pair of sash frames seated therein, a parting strip dividing said sash 80 frames and having interlocking engagement with the latter, and means for locking said parting strip to the casing comprising a socket member provided with inwardly inclined tongues, a stud seated in said socket 85 and having grooves at opposite sides to receive said tongues, said stud having longitudinal movement in said socket, and a screw bolt extending through the face of the parting strip and detachably holding 90 the stud against longitudinal movement in its socket.

2. In a fireproof window, a side casing member provided with a longitudinal jamb channel, a pair of sash frames seated in said channel, a T-shaped parting strip formed of sheet metal, said sashes having grooves for receiving the head of said parting strip, said jamb having a rectangular countersunk portion into which the end of said parting strip 95 extends a distance, a block at the inner end of said countersunk portion and having side grooves, the inner corners of said countersunk portions having slots, tongues having hooked ends extending through said slots 100 and having their other ends engaging in the grooves of said block whereby said block is anchored to the inner end of said countersunk portion, and a screw swiveled in the head of said parting strip and having 105 threaded engagement with said block whereby said parting strip may be adjusted toward and away from said jamb.

3. In a fireproof window, a side casing member provided with a longitudinal jamb 115 channel having an intermediate rectangular countersunk portion, a sash frame engaging with said jamb at each side of said countersunk portion, the opposed faces of said sash frames having grooves, a T-shaped parting 120 strip built up of sheet metal and having the sides of its head engaging in the sash frame grooves, the inner end of said parting strip telescoping a distance into said rectangular countersunk portion, a block at the inner 125 end of said countersunk portion having grooves in its opposed sides, there being slots at the inner corners of said countersunk portion, tongues having hooked ends engaging in said slots and having their in- 130

ner ends engaging in the block grooves whereby said block is securely anchored at the inner end of the countersunk portion, a reinforcing strip secured to the inner side 5 of the head of said parting strip, a screw having its head swiveled in said reinforcing strip, and a pin extending through the screw shank at the inner surface of said reinforcing strip to lock said screw to said strip, the 10 inner end of said screw having threaded en-

gagement with said block within the countersunk portion whereby turning of the screw will effect adjustment of the parting strip head toward or away from said side casing.
